Primary Examiner—Ruth McInroy*Attorney, Agent, or Firm*—Dorsey & Whitney LLP[57] **CLAIM**

The ornamental design for a handle for floor care apparatus, as shown and described.

DESCRIPTION

FIG. 1 is a rear, left isometric view of a handle for floor care apparatus showing our new design;

FIG. 2 is an enlarged rear, left isometric view thereof;

FIG. 3 is an enlarged left side elevational view thereof;

FIG. 4 is an enlarged front elevational view thereof;

FIG. 5 is an enlarged rear elevational view thereof;

FIG. 6 is an enlarged top plan view thereof; and,

FIG. 7 is an enlarged bottom plan view thereof.

The details shown in broken lines in all views are for illustrative purposes only and form no part of the claimed design.
